OR D 11,874

No. 11,874

July 20, 1880

UNITED STATES PATENT OFFICE.

TOBIAS S. HEISTER, OF LANSINGBURG, NEW YORK, ASSIGNOR TO OTIS G. CLARK AND DANIEL D. BUCKLIN, EXECUTORS OF THE LAST WILL OF N. S. VEDDER, DECEASED.

DESIGN FOR ELEVATED-OVEN COOKING-STOVE.

SPECIFICATION forming part of Design No. 11,874, dated July 20, 1880.

Application filed June 14, 1880. Term of patent 3½ years.

To all whom it may concern:

Be it known that I, TOBIAS S. HEISTER, of Lansingburg, in the county of Rensselaer and State of New York, have invented and produced a new and original ornamental Design 5 for Elevated-Oven Cooking-Stoves, of which the following is a specification, reference being had to the accompanying cut, print, or engraving of a stove having my said new design.

One part of my invention is the design for the front plate of the elevated oven, the same consisting of the central tablet-frame, A, having angular side projections, b, and arched end 15 pieces, c, the ornamented columns F F, the arch D, with keystone e, connecting said columns, and the end ornaments, G, all shaped and disposed substantially as represented in the aforesaid cut.

Another feature is the design for the end doors of the elevated oven, the same consisting of the compound panel ornament H, composed of the central flower-stem, i, inclosed by the base part, j, side columns, k, and arched top 25 l, with keystone therein, the panel-surface m, the inner border ornamentation, n, and the outer ornamental border, o, all shaped and arranged substantially as represented in the accompanying engraving.

Another feature is the design for the door 30 or panel P at the end of the fire-box, the same being composed of the compound central ornament, q, surface r; ornamental inner border, s, ornamented outer border, t, and intervening surface u, all shaped and combined substantially as shown in the aforesaid print. 35

What I claim as my invention is—

1. The design for the front plate of the elevated oven, consisting of the parts A b c, D e, F F, and G, all shaped and arranged together 40 as shown and described.

2. The design for the end doors of the elevated oven, consisting of the parts H i j k l, m, n, and o, all shaped and arranged together 45 as set forth.

3. The design for the door or panel P, consisting of the parts q r s t u, all shaped and arranged together as described and shown. 45

In testimony whereof I hereunto set my hand, in the presence of two subscribing witnesses, 50 this 9th day of June, 1880.

TOBIAS S. HEISTER.

Witnesses:

JAMES A. GILMAN,
CHESTER BASCOM.
